United States Patent Office

Des. 186,409
Patented Oct. 20, 1959

186,409

FRAME FOR A HARP

Samuel O. Pratt, Chicago, Ill., assignor to Lyon & Healy,
Inc., Chicago, Ill., a corporation of Illinois

Application December 24, 1958, Serial No. 53,895

Term of patent 14 years

(Cl. D56—1)

Des. 186,409

PAGE 2

Des. 186,409

PAGE 3

Figure 1 is a perspective view of a frame for a harp showing my new design;

Figure 2 is a front elevational view thereof;

Figure 3 is a rear perspective view of the sounding box portion thereof, the remainder of the harp being omitted for convenience of illustration;

Figure 4 is a side elevational view thereof;

Figure 5 is an enlarged fragmentary top plan view thereof taken along line 5—5 of Figure 4; and

Figure 6 is an enlarged fragmentary sectional view thereof along line 6—6 of Figure 4.

I claim:

The ornamental design for a frame for a harp, as shown.
